ABSTRACT OF THE DISCLOSURE

A liquid container made at least partially of translucent material and having a plurality of indentations in at least one surface thereof and a label of light-reflecting material having a plurality of identification markings thereon. The label is attached over the indented surface and, depending on the data to be recorded, portions of the label with identification markings thereon are partially severed from the label surface and pushed inwardly to enter the indentations. With these partially severed portions pushed inwardly light rays projected on to a translucent surface of the container extending substantially transversely to the label bearing translucent surface will pass through the container behind the label and be deflected by the inwardly pushed reflecting label portions out through the label bearing surface for visual or mechanical observation.

This invention relates to the recording of data and is concerned with a method of marking a labelled container and apparatus for recording data relating to the contents of a container.

The invention is particularly suitable for use in hospitals where it is desired to record data relating to blood or other liquid samples obtained from patients. With each such sample, there must be an indication of the origin of the sample, for example the patient from whom the sample was obtained and the hospital or clinic attended by the patient.

According to the invention there is provided a method of marking a labelled at least partially translucent container to identify the contents thereof, the container label having a plurality of identification markings on a light-reflecting surface thereof and being attached on a translucent surface of the container having a plurality of indentations therein with said identification markings each overlying an indentation, wherein at least one selected portion of the label bearing markings is partially severed and pushed inwards relative to the label surface to enter the underlying indentation in such manner that the container marking may subsequently be observed by passing light rays through a further translucent surface of said container extending substantially transversely to the label bearing surface and behind the label to fall on the reflecting surface of said pushed in label portion and be deflected thereby out through said label bearing surface at a location determined by said pushed in label portion.

For carrying out the above method the invention further provides the combination of a liquid container made at least partially of translucent material and having at least one translucent surface provided with a series of indentations and a label of light-reflecting material having a plurality of identification markings thereon and being attached or attachable over said container surface with said markings each overlying an indentation in such manner that one or more selected portions of said label may be partially severed and pushed inwards relative to

2

the label surface to enter the underlying indentation thereby to provide one or more deflecting surfaces for changing the course of light rays when projected on to a further translucent surface of the container extending substantially transversely to the label bearing surface of the container to pass through the container behind the label and fall on said deflecting surface or surfaces and be deflected thereby out of the label bearing surface of the container at a location or locations determined by the or each inwardly pushed label portion.

In order that the invention may be more clearly understood and readily carried into effect, one embodiment of a container will now be described in greater detail with reference to the accompanying drawing in which:

FIGURE 1 is a side elevation of a liquid container of the invention.

FIGURE 2 is a front elevation of the container shown in FIGURE 1,

FIGURE 3 is a view, similar to FIGURE 2, and shows the container provided with an identification label, and

FIGURE 4 is drawn on a larger scale and shows the container of FIGURES 1 to 3 located in an inspection stand.

Referring now to the drawing, a liquid container 1 of rectangular configuration is made of glass, plastics or other transparent material. Such a container is conveniently made of a high duty clear polystyrene. The front and rear surfaces 2 and 3 respectively of the container 1 are large in comparison to the end edges 4 and 5 and the side edges 6 and 7 thereof and the container, which is closable by a cap (not shown) of similar material, is dimensioned to contain approximately 5 cc. of liquid.

The front surface 2 of the container 1 has a series of parallel grooves 8 channelled therein and extending from the top edge 4 to the bottom edge 5 thereof. In the embodiment illustrated there are six such grooves.

In order to record data relating to a liquid contained in the container 1 a label 9 of metal foil or other light reflecting material is attached on the front surface 2 over these grooves 8. The label 9 is attached by a suitable adhesive to the ridges 10 separating the grooves 8 and, as shown in FIGURE 3, has six columns of figures arranged in such manner that with the label attached on the front surface as aforesaid, the columns extend one above each of the grooves. In a preferred embodiment, a pressure sensitive adhesive is used to attach the label 9 to the container 1. The figures in the columns are set out in the manner of a conventional punch card with ten digits—zero to nine—in each column and with similar digits positioned side-by-side in adjacent columns.

The label 9 is comprehensively perforated so that perforations extend around three sides of each digit. The fourth side of each digit is left unperforated and in this manner the label portions bearing the digits may selectively be pressed out of the plane of the label and pushed inwardly into the associated grooves by rupturing the perforations with a blunt tool and hinging the digit bearing portion about the unperforated side. FIGURE 4 shows three digit bearing label portions pushed inwardly into the associated grooves in this manner.

The inwardly hinged label portions are not bent at right angles to the remaining label surface but, as shown in FIGURE 4, are deflected inwardly through approximately 45°.

In order clearly to indicate each pushed-in label portion the container 1 is placed in a stand and a beam of light is directed into said container through a side edge thereof which is normal to the label bearing surface. This light beam passes through the transparent container wall behind the label and is deflected out of the label bearing surface by the inwardly hinged label portion. Although

FIGURE 4 illustrates a preferred embodiment of the invention to be described hereinafter in which both the front surface 2 and the rear surface 3 of the container 1 each have a label attached thereon, this figure clearly shows how light rays 11 from a source 12 pass through the side edge 6 and are reflected forwardly at 13.

If one digit bearing label portion in each column is pushed inwardly as aforesaid, then a pattern of light dots will show up on the label surface when the beam of light is directed on the side edge. Furthermore, if the digit bearing portions are pushed inwardly in a pattern determined by the liquid in the container, for example to denote a given six figure reference number, then this pattern will be sufficient at some later date to denote the contents of the container.

The pattern of light may obviously be observed and recorded visually but advantageously an automatic scanning is effected by a bank of photoelectric cells (not shown). During such a scanning operation it is important that the container be correctly orientated to ensure that the light pattern is correctly read. To this end the container is provided with a slot or keyway 14 to facilitate location thereof during said scanning operation.

As stated hereinbefore, advantageously both front and rear surfaces 2 and 3 are grooved as aforesaid and light reflecting labels 9, 9' are attached on these opposite surfaces of the container and the amount of information which may be recorded is increased accordingly.

As stated hereinbefore, the digit bearing portions of the label are preferably hinged inwardly through approximately 45°. To support these inwardly hinged portions in position, one edge wall of each groove is bevelled to provide a support surface 15 which is upwardly inclined at the desired angle. On hinging a label portion inwardly as aforesaid, the pressure sensitive adhesive will permanently adhere said portion to the support surface 15 of the associated groove. The bevelled wall support surface of each groove is obviously that which is furthest from the container side edge through which the light beam passes.

In the case of six grooves, each of the three grooves to one side of the centre line of the container advantageously has a bevelled wall inclined in such manner that digit bearing label portions are directed towards one side edge of the container whereas each of the three grooves on the opposite side of the centre line has a bevelled wall which is inclined in such manner that the digit bearing label portions are directed towards the opposite side edge of the container. With this arrangement, as shown in FIGURE 4, two light sources 12, 12' are positioned one on each side of the container 1 for scanning or illuminating as aforesaid.

For scanning or illuminating the light from the or each source is not projected in a parallel path on to the respective side edge of the container since light travelling in a parallel path would be deflected from the first inwardly hinged label portion encountered and not from any subsequent hinged portions in line therewith. The light is therefore projected in the manner shown in FIGURE 4 at an angle on to the respective side edge of the container.

The container of the invention is particularly suitable for use in hospitals and if labels are attached on the front and rear surfaces as aforesaid, then one label may be used to record a patient's personal number and the other label may be used to record the code number of the hospital or clinic attended.

In the above-described embodiment the container 1 is closable by a separate cap (not shown). However, in certain circumstances, the container may be closed by an extension of the self-adhesive light-reflecting label.

As stated hereinbefore, the container is transparent and with such a container the contents, for example a blood sample, may be optically inspected through the side edges. However, although advantageously transparent, it will be appreciated that it is only essential for

the container to permit the passage of light rays therethrough and, in fact, a translucent but not transparent container would serve this purpose. Furthermore, it will be appreciated that only those parts of the container through which light rays will pass must be translucent and it would therefore be possible to employ a container in which only these parts are translucent.

Advantageously, the inside of the container 1 is chemically treated with anti-coagulants when said container is used for storing blood samples. Furthermore, in cases where it is necessary to centrifuge blood samples prior to inspection, the container, which is of suitably rugged construction, may be inserted directly into a centrifuging machine.

Finally, if desired, the label 9 may be provided with a tear-off extension (not shown) on which details of the patient and the sample origin or other memoranda may be written.

We claim:

1. A method of marking a labelled at least partially translucent container to identify the contents thereof, the container label having a plurality of identification markings on a light-reflecting surface thereof and being attached on a translucent surface of the container having a plurality of indentations therein with said identification markings each overlying an indentation, said method comprising the steps of partially severing at least one selected portion of the label bearing an identification marking and pushing said partially severed portion inwardly into the underlying indentation whereby the container marking may subsequently be observed by passing light rays through a further translucent surface of the container extending substantially transversely to the label bearing surface and behind the label to fall on the reflecting surface of said pushed in label portion and be deflected thereby out through said label bearing surface at a location determined by said pushed in label portion.

2. The combination of a liquid container having a series of indentations in at least one translucent surface thereof and a label of light-reflecting material having a plurality of identification markings thereon, said label being attachable over said container surface with said markings each overlying an indentation whereby at least one portion of said label bearing an identification marking may be partially severed and pushed inwards relative to the label surface to enter the underlying indentation and light rays may be projected on to a further translucent surface of the container extending substantially transversely to this label bearing surface to pass behind the label and fall on said inwardly pushed label portion and be deflected thereby out through the label bearing surface of the container.

3. A combination as claimed in claim 2 wherein the container having translucent surfaces is at least partially transparent.

4. A combination as claimed in claim 2 wherein a series of indentations are provided on each of two opposite outer surfaces of the container adapted to receive a label of light-reflecting material.

5. A combination as claimed in claim 2 wherein indentations in the label bearing surface are in the form of a series of grooves each extending substantially from top to bottom of said surface.

6. A combination as claimed in claim 5 wherein one wall of each groove is bevelled to form an angled seating for an inwardly pushed portion of the label in such manner that, with said portion seated on the bevelled wall part, light rays projected on to a surface of said container extending substantially transversely to the label bearing surface and passing through said container behind said label will fall on the inwardly pushed label portion and be deflected thereby.

7. A combination as claimed in claim 6 wherein the bevelled walls of the grooves are directed in such man-

ner that light rays passed through the container behind the label from each side thereof will fall on the deflecting surfaces of inwardly pushed label portions.

8. A combination as claimed in claim 2 comprising perforations around three sides of each identification marking on the label of light-reflecting material to facilitate partial severing thereof and pushing the partially severed portion inwardly to enter the associated indentation.

9. A combination as claimed in claim 2 wherein an extension of the label is adapted to close the container.

10. A combination as claimed in claim 2 comprising means provided on the container to facilitate the de-

sired positioning thereof during observation of the location of deflected light rays.
